Calif., a corporation of Delaware

Application October 25, 1946, Serial No. 705,660

12 Claims. (Cl. 263—43)

1

This invention relates to an improved method for heating various materials, by indirect heat exchange with hot combustion gases, and apparatus therefor.

An object of the invention is to provide a method and apparatus for heating by indirect heat exchange with combustion gases whereby the temperature throughout the heating zone is exceptionally uniform and easily and accurately controllable. Another object of the invention is to provide a method and apparatus for heating whereby heat transfer is greatly increased through conduction. An object of the invention is to provide a method and apparatus for heating which is particularly advantageous in carrying out chemical reactions and conversions wherein a uniform and controlled temperature throughout a definite reaction space is desired.

In the usual method of heating by indirect heat exchange with combustion gases the material to be heated is placed in or passed through a suitable enclosed chamber, usually a coil or tube, and the combustion gases from a surrounding or adjacent combustion zone are caused to pass over and about said chamber and exchange heat therewith. The simplest case is the steam boiler. In this system, large variations in temperature occur in the combustion zone; a large part of the heat transfer is by radiation and consequently there is a great tendency to develop hot spots. These conditions are very undesirable in all cases where a uniform controlled temperature is desired, as for example when carrying out chemical conversions. In order to adapt this simple system to chemical conversions, numerous modifications and variations have been made in attempts to overcome these disadvantages. One of the most successful of these is the so-called Petro-Chem Iso-Flow furnace now in wide use. In this type of furnace, however, the heat transfer rate is very low. Also, the temperatures are still not as uniform as would be desired. This is especially the case where a chemical conversion is being carried out which is either appreciably exothermic or endothermic, since it is extremely difficult if not impossible to adjust and compensate for variations in the quantity and position of the liberated or absorbed heat of reaction.

While the above-mentioned simple system and its variations are the most common, the Bonecourt system should be mentioned. In this system, a homogeneous explosive mixture of gas and air in the proper ratio for complete combustion is caused to burn without flame by pass-

2

ing up through a stationary bed of granules of incandescent refractory. A particularly large proportion of the potential energy is thereby converted into radiant energy. This system is particularly advantageous where very high temperatures (higher than those readily obtainable by the more common method) are desired. Due to the large proportion of radiant energy there is a great tendency to develop localized zones of very high temperature. Also, the system is not suitable for operation at the relatively low temperatures (for instance below 1000° F.) usually desired for chemical conversions.

In the system of the present invention, exceptionally uniform temperatures throughout the entire heating zone are obtained. The temperature may furthermore be easily and accurately controlled. Also uniform, controlled heating at relatively low temperatures, for instance below 1000° F., as well as higher temperatures, may be effected. These advantages or points of superiority are attained by effecting the combustion of a fuel gas within the body of an agitated finely divided solid heat carrier which in turn exchanges heat indirectly with the material to be heated. Thus, in the present system, the combustion zone is filled with a substantially static bed of finely divided inert solid; fuel gas and an oxygen-containing gas are injected into the body of the finely divided solid under combustion conditions at such a rate as to maintain the finely divided solid in a violently agitated fluidized or pseudo-liquid condition.

The process of the present invention will be described and explained in more detail in connection with the description of the apparatus illustrated in the attached drawing. In the interest of clearness the apparatus illustrated in the attached drawing is shown semi-diagrammatically in somewhat simplified form. For instance, none of the steel framework and supporting structure is shown. Tube 4, which carries the fluid to be heated is shown as a single coil, whereas in practice the apparatus often will contain several tubes with separate inlets and outlets.

Figure I is an elevational view of the section I—I indicated in Figure II;

Figure II is a plan view of the section II—II indicated in Figure I;

Figure III is a plan view of the section III—III indicated in Figure I.

Referring to the drawing, 1 is a furnace or housing structure having inner walls of refractory

material, and built to define a combustion zone 2 and a so-called disengaging zone 3.

The combustion zone, as indicated in Figures I and III, is rectangular in plan. While this rectangular plan of the combustion zone is particularly suitable in most cases, the apparatus is not limited in this respect. Thus, by suitable rearrangement of the pipes, etc., combustion zones of any desired horizontal section such as circular, oval, square, etc., may be used. The combustion zone is substantially completely filled with a finely divided inert solid as will be described in more detail below. The combustion zone therefore extends from substantially the bottom up to the level of the finely divided solid (see Figure I). A suitable tube 4 designed to carry the fluid to be heated, and preferably of heat resistant alloy, is suitably supported (by means not shown) within the combustion zone. In the apparatus illustrated, the tube 4 runs lengthwise and horizontal except for the return bends. In most cases when a fluid reactant or reactants are to be heated, horizontal tubes are quite suitable. In such cases where the tube or tubes contain a solid fixed catalyst, it is desirable that the tube be placed at an angle of at least 30° from the horizontal. The projecting ends of tube 4 and the outer surface of the furnace may be insulated (not shown). In such cases where there are a plurality of tubes or a coil such as illustrated, sufficient space should be provided between the tubes or turns of the coil to allow circulation of the fluidized solid. It is desirable to place the tubes or turns of the coil in the combustion zone so that a space equal to one tube diameter or somewhat more is provided between the individual tubes or turns. The most suitable diameter and number of the tubes or coils will vary with the temperature and heat transfer requirements. The spacing and the ratio of tube heating surface to volume will be adjusted in any particular case according to known engineering principles to provide the requirements of heat transfer and residence time of the particular operation contemplated.

The fuel for the apparatus is fuel gas such as water gas, producer gas or natural gas. This gas is supplied by line 14 and is introduced into the combustion zone near the bottom by means of two parallel perforated pipes 8 and 9. Other equivalent means may be provided. Air or other gas containing sufficient oxygen for the combustion of the fuel gas is supplied by blower 10 and line 11 and is introduced into the combustion zone, preferably at a plurality of points, by the perforated section of pipe 13 at the bottom of the combustion zone. It is found desirable to preheat the air prior to introducing it into the combustion zone. This is accomplished in the apparatus illustrated by passing the air through coil 12 which is connected to the perforated section 13 by line 15. Since in this case the heat required for preheating is obtained from the combustion zone, it is seen that this arrangement is designed to give more uniform combustion rather than to allow the attainment of higher temperatures. If higher temperatures are desired, the preheating of the air and/or fuel gas should be effected outside of the combustion zone, as for instance in a separate preheater or by placing the preheating coils in the disengaging space. In the apparatus illustrated, the fuel gas and air are independently introduced into the combustion zone, the air only being preheated. It is to be understood that the fuel gas and air

may be introduced as a mixture which may or may not be preheated. In general, however, preheating is advantageous.

The space 3 immediately above the level of the finely divided inert solid is called the disengaging zone. This zone is preferably of larger horizontal cross-section than the combustion zone. It is preferably at least 3 ft. in height, but may be somewhat less in some cases where the finely divided solid material is particularly dense and the disengaging zone is larger in horizontal cross-section than the combustion zone. The hot combustion gases leave the disengaging space by means of conduits 16 and 17. This hot gas usually carries in suspension a minor amount of the finely divided solid from the combustion zone. It is therefore preferably passed to a means for the recovery of this solid. Thus, this gas is passed to cyclone separators 18 and 19. The gas, substantially free of suspended solids, is then discharged via line 20, blower 21 and line 22. It is often necessary to recycle a portion of this hot gas to the combustion zone. For this purpose the apparatus is preferably provided with suitable inlet tubes such as tube 23 feeding from manifold line 24. The desired portion of the gases to be thus recycled is supplied to manifold 24 by line 25 and blower 21. In some cases it will be found desirable for temperature control to cool the gas somewhat. This may be accomplished by injecting water or steam into the fluidized powder or into the disengaging space. Nozzles 28 and 29 are provided for this purpose. When injecting steam or water into the fluidized powder the cooling effect is more pronounced; however, by injecting it into the disengaging zone the gas velocity in the combustion zone is not affected. Also, if desired, suitable heat exchange equipment or a waste heat boiler or the like may be used to recover additional heat from the combustion gases prior to discharging them.

Finely divided solid collected by the cyclone separators may be fed to manifold line 24 by lines 26 and 27. This material is then blown back into the combustion zone by the recycled gas.

The apparatus is also provided with one or more separate burners for fuel gas, oil, or any other fuel located in the disengaging space. In Figures I and II this is indicated by the single burner 5 supplied with gas and air by lines 6 and 7.

In operation the finely divided inert solid material filling the combustion zone is maintained in a so-called fluidized or pseudo liquid state having a density of at least 20 lbs./cubic foot. This pseudo liquid completely fills the combustion zone, exhibiting a more or less definite upper level, as indicated. The pseudo liquid is in violent agitation; if a small amount of lampblack is added it is seen to be evenly dispersed throughout the zone in a few seconds. In order to permit the attainment of this pseudo liquid condition the inert solid should be sufficiently finely divided that at least most of it passes a 40-mesh U. S. Standard sieve. Larger particles may be present but only in conjunction with a sufficient quantity of the finer particles. For instance, particles having diameters between about 20 microns and 500 microns are suitable. In spite of the violent agitation in the combustion zone, it is found that there is little eroding of the particles in the system and consequently little carry-over of the material to the cyclone separators. In some

cases, in fact, the cyclone separators may be dispensed with. The desired degree of fineness may be produced by grinding.

However, in order that the desired fluidized condition of the finely divided solid may be easily obtained, particularly in starting up, it is most desirable, but not essential, that the finely divided solid particles be more or less spherical in shape. The use of particles of such shape also has the great advantage of allowing the desired fluidized condition to be maintained in operation over a greater range of gas velocities, thus increasing the range of application and facilitating the control of the apparatus.

The composition of the inert solid may vary and is preferably chosen in accordance with the particular case. In general, the more important desired properties of the solid material are

(1) It should be capable of withstanding the temperatures prevailing in the combustion zone without fusing or sticking.

(2) It should have a high coefficient of heat conductivity.

(3) It should not be consumed or destroyed by the combustion.

Thus, when relatively low temperatures are to prevail in the combustion zone a material having a high coefficient of heat conductivity, such as metal powder, powdered metal oxides (for instance, iron oxide), and the like, is preferably chosen. Such material may have a relatively low fusion point. When higher temperature is to prevail in the combustion zone a more refractory material such as silicon, silica, alumina, zirconia or the like is chosen, even though such materials generally do not have particularly good coefficients of heat transfer.

Some further particulars regarding the process and apparatus of the invention are best made evident by a description of an operation. Since the process of the invention is particularly advantageous for carrying out chemical conversions of a highly exothermic or endothermic nature at relatively low temperatures, a process of this type is chosen to illustrate the operation. Thus, the operation of the process will be described in connection with the dehydrogenation of methylcyclohexane to toluene with a tungsten sulfide-nickel sulfide catalyst. For this endothermic conversion a series of tubes connected to common headers instead of the single tube 4 is preferred. Also, since the tubes are substantially filled with a bed of the catalyst pellets, the tubes are preferably inclined rather than horizontal. These variations however have no bearing upon the functioning and control of the heating system described.

The finely divided solid may be, for example, particles of zirconia chiefly from about 100 microns to about 500 microns in diameter. There are thirty-two 3-inch alloy reaction tubes, 24 feet long, in the combustion zone. The apparatus has a heat adsorption capacity of about 10 mm. B. t. u. per hour and a thermal efficiency of about 65%, excluding the power drives for the blowers.

In starting the apparatus valve 30 is throttled, valve 31 is opened and blower 21 is started. The amount of air circulated is adjusted by means of the valves and/or the blower to bring the powder into the desired fluidized state. Burner 5 is started. When the temperature of the finely divided solid reaches about 600° F. or somewhat higher, blower 10 is started and natural gas is

introduced via line 14. The total introduction of gas into the combustion zone is regulated to give a superficial gas velocity of about 2 feet per second. The finely divided zirconia is then in an agitated fluidized state having a density of about 30-40 lbs./cubic foot. When the temperature in the combustion zone reaches the desired temperature, for instance 1200° F., burner 5 is shut off, valve 30 is adjusted and methylcyclohexane is passed through the reaction tubes. The temperature is then controlled by control of the natural gas and air supplied to the combustion zone. The density and agitation of the powder may be adjusted by adjusting the amount of gas recycled. The gas which is not recycled is discharged via line 22.

A small amount of zirconia powder collects in the cyclone separator. This is re-introduced into the combustion zone by means of the recycled gas as described.

In some cases it is desirable to inject steam or water by injection nozzles 28 and 29. This is often the case where a low-temperature highly exothermic process is being carried out. In such cases the flows of gaseous fuel and air are low and the amount of recycle gas is quite large. The combustion may then be improved by increasing the flows of gaseous fuel and air, decreasing the recycle gas flow, and cooling the recycle gas by the injection of steam or water.

The illustrated apparatus is intended for operation at substantially atmospheric pressure. The combustion takes place under positive pressure, however, due to the "hydraulic" head of the powder in pseudo liquid state. It will be appreciated, however, that the process of the invention is also applicable for operation in which the combustion zone is maintained under a higher pressure if an apparatus capable of operation under such pressure is provided. Operation under a positive pressure has some advantages. However the greatly increased cost of the apparatus designed to operate under high pressure makes the use of such pressure unattractive for at least most cases.

The invention claimed is:

1. An apparatus of the class described comprising a furnace structure having inner walls of refractory material defining a lower combustion zone and an upper disengaging zone, a bed of fluidized powdered inert refractory solid substantially filling said combustion zone, a coil or tube within said combustion zone provided with external connections for passing a fluid to be heated therethrough, an ancillary burner above said combustion zone in said disengaging zone, a conduit for combustion products connecting said disengaging zone with a dust separator, a conduit for gases provided with a blower connecting the gas outlet of said separator with said combustion zone near the bottom thereof and means for injecting a gaseous fuel and oxygen into said combustion zone near the bottom thereof.

2. An apparatus of the class described comprising a furnace structure having inner walls of refractory material defining a lower combustion zone and an upper disengaging zone, a bed of fluidized powdered inert refractory solid substantially filling said combustion zone, a coil or tube within said combustion zone provided with external connections for passing a fluid to be heated therethrough, an ancillary burner above said combustion zone in said disengaging zone,

a conduit for combustion products connecting said disengaging zone with a dust separator, a conduit for gases provided with a blower connecting the gas outlet of said separator with said combustion zone near the bottom thereof and means for separately injecting a gaseous fuel and oxygen into said combustion zone near the bottom thereof.

3. An apparatus of the class described comprising a furnace structure having inner walls of refractory material defining a lower combustion zone and an upper disengaging zone, a bed of fluidized refractory inert powder consisting of particles of spheroidal shape between about 20 microns and 50 microns in diameter substantially filling said combustion zone, a coil or tube within said combustion zone provided with external connections for passing an ancillary fluid to be heated therethrough, a burner above said combustion zone in said disengaging zone, a conduit for combustion products connecting said disengaging zone with a dust separator, a conduit for gases provided with a blower connecting the gas outlet of said separator with said combustion zone near the bottom thereof and means for injecting a gaseous fuel and oxygen into said combustion zone near the bottom thereof.

4. An apparatus according to claim 1 further provided with means for preheating gases, communicating with said means for injecting fuel gas and air into said powdered solid near the bottom of said combustion zone.

5. An apparatus according to claim 1 further provided with means for returning solid particles collected in said separating means to the combustion zone.

6. The method of heating by indirect heat exchange with hot combustion gases material to be chemically reacted which comprises passing said material in indirect heat exchange relationship through a combustion zone, maintaining said combustion zone filled with a substantially static bed of an inert and non-combustible refractory powder, and supplying a gaseous fuel and an oxygen-containing gas within said powder under combustion conditions at such a rate as to maintain said powder in a pseudo-liquid condition whereby the material being heated is brought to a suitable uniform reaction temperature.

7. Method according to claim 6 in which the inert and non-combustible refractory powder consists essentially of particles within the range of from about 20 microns to about 500 microns.

8. Method according to claim 6 in which the inert and non-combustible refractory powder consists essentially of substantially spherical particles.

9. Method according to claim 6 in which the

inert and non-combustible refractory powders consist essentially of rounded particles of zirconia.

10. Method according to claim 6 in which the density of said inert and non-combustible refractory powder in pseudo-liquid condition is at least 20 pounds per cubic foot.

11. The method of heating by indirect heat exchange with hot combustion gases material to be chemically reacted which comprises passing said material in indirect heat exchange relationship through a combustion zone, maintaining said combustion zone filled with a substantially static bed of an inert and non-combustible refractory powder, supplying a gaseous fuel and a gas containing free oxygen within said powder under combustion conditions at such a rate as to maintain said powder in a pseudo-liquid condition, and regulating the temperature in said combustion zone by controlling the ratio of fuel gas to oxygen whereby the material being heated is brought to a suitable uniform reaction temperature.

12. The method of heating by indirect heat exchange with hot combustion gases material to be chemically reacted which comprises passing said material in indirect heat exchange relationship through a combustion zone, maintaining said combustion zone filled with a substantially static bed of an inert and non-combustible refractory powder, supplying a gaseous fuel and an oxygen-containing gas within the body of said powder under combustion conditions at such a rate as to maintain said powder in a pseudo-liquid condition, and controlling the temperature in said combustion zone by the addition of regulated quantities of steam whereby the material being heated is brought to a suitable uniform reaction temperature.
